CABINET FOR HOUSING ELECTRONIC CONTROLS

Ralph L. Jaeschke, Kenosha, Wis., assignor to Eaton
Yale & Towne Inc., Cleveland, Ohio

Filed Mar. 12, 1970, Ser. No. 21,872

Term of patent 14 years

Int. Cl. D14—02

U.S. Cl. D26—5

FIG. 1 is a front perspective view of a cabinet for housing electronic controls.

FIG. 2 is a front view of my invention.

FIG. 3 is a side view of my invention.

The side not shown is a mirror image of the side shown while the back is plain and unornamented.

I claim:

The ornamental design for a cabinet for housing electronic controls, as shown and described.
